UNITED STATES PATENT OFFICE.

JOSEPH BECKER, OF WASHINGTON, DISTRICT OF COLUMBIA.

FOCUSING-CAMERA.

1,190,623.

Specification of Letters Patent. Patented July 11, 1916.

Application filed June 15, 1901. Serial No. 64,722.

To all whom it may concern:

Be it known that I, JOSEPH BECKER, a citizen of the United States, residing at Washington, District of Columbia, have invented certain new and useful Improvements in Focusing Cameras, of which the following is a specification.

The present application is identified for convenience of reference in my related applications or patents as Case D; and the present specification hereinafter makes specific reference to my related applications or patents as follows: Case A, now Patent 1,178,474, issued April 4, 1916; Case B, Now 15 Patent 1,178,475, issued April 4, 1916; Case C, now Patent 1,178,476, issued April 4, 1916; Case W, Serial No. 696,197, filed May 9, 1912, as a division of the present application, Case D.

20 My present invention relates to "optical focusers" of the type disclosed in my said prior Cases A, B, and C, in which the operation of focusing is reduced to the act of virtually sighting the object point to be focussed on from two laterally separated station points on the camera. All focusers shown in my said prior Cases A, B, and C, including even the funicular focusers of Figs. 14 to 16 of my said Case A, comprise one or 25 more structural elements that are pivoted; whereas, the novel focusers herein described do, without rotations, by means of pure translations, accomplish the same final result, to wit: secure proper coördination of 30 camera extensions with ray inclinations. In order, however, to connect my present invention logically with the basic invention disclosed in my said Case A, I am first showing a special pivoted mirror form of focuser 35 which closely resembles the focuser shown in my said Case B and is easily converted into a form containing no rotating elements whatever.

In the accompanying drawings: Figure 1 40 is a side elevation of a camera in which the exterior relatively movable images are formed by a fixed mirror, a pivoted mirror, and a divergent lens; Fig. 2 is a view looking from right to left in Fig. 1, showing 45 how the optical parts would appear with both mirrors fixed in parallel relation and the lens divided to produce displacements of the images by shifting one lens section by the other; Fig. 3 is a perspective view 50 of an equivalent combination made of glass prisms; Fig. 4 is a side elevation of a camera

provided with the optical elements of Fig. 3. Fig. 5 is a sectional view of an arrangement in which the relatively movable images are produced by means of two diminutive cameras and a prism; Fig. 5^a is a view looking in the direction of arrow 18, Fig. 5, the camera proper being omitted; Fig. 6 is a sectional view of another form in which the relatively movable images are produced by means of divergent lenses and a prism; Figs. 7 and 8 are variations of Figs. 5 and 6, respectively; Fig. 9 is a side elevation of a camera in which the relatively movable images are formed by two eccentric lens elements and a screen; Figs. 10 and 11 are diagrams illustrating the optical principles involved in the focusers of Figs. 1 to 4.

The specific form of my invention that I have elected to support the more specific 75 claims of the present application, Case D, is that illustrated in Figs. 2 to 4 with the aid of Fig. 1. The forms of Figs. 5, 5^a, 6, 7, 8 and 9, all characterized by the fact that the relative movements of the focuser elements 80 are the same in direction and extent as the relative focusing movements of the camera lens and camera plate or film, constitute the subject-matter of a separate application, my said Case W.

85 The fundamental principle of the mirror type is made clear in Fig. 1, where M and N represent two parallel mirrors and S a lens, preferably of short negative focus. The mirrors form, of any object I, an image I', which is shifted up and back of I through a distance II' or $2d$ equal to twice the distance d between the planes of the two mirrors exactly as in Fig. 13 of my said Case A, Fig. 9 of my said Case B, and Fig. 8 of 90 my said Case C.

95 Lens, S, forms of object I and of its image, I', small images, i i' , which are very nearly in the principal focal plane of the lens the effect being substantially the same 100 as illustrated in Fig. 9 of my said Case B, and in Fig. 8 of my said Case C. Mirror, N, being opaque, must conceal all of image, i , that lies behind it; but, it will simplify 105 matters to first consider this mirror as being of illimitless extent, but transparent as well as reflecting. In this case both images, i and i' , will be perceived in full at the same time and the apparent distance between their centers can be seen to be almost inversely 110 proportional to the distance of point, I, from lens, S; that is to say, the distance from the

center of i to the center of i' will appear to be very small or practically *nil* when I is very distant, and it becomes gradually larger as I approaches.

5 Images, i and i' , of point, I , can always be brought into register or coincidence by moving some part of the optical combination and the extent of motion required to secure coincidence corresponds to the distance between said images. On the other hand, when a camera in focus on infinity is to be focused on a point that is close, its depth must be increased by a certain amount which is greater as the object comes closer and this 10 increase in depth is also very nearly inversely proportional to the distance of the object. Hence, if a camera is mounted in combination with an optical arrangement, such as that of Fig. 1, the motions of the 15 camera to keep it in focus on a moving point, I , will correspond to those that must be made in the optical arrangement to keep the images, i and i' , in coincidence and this correspondence can be secured by the trial 20 adjustment of proper mechanical connections, as fully explained in my said Cases A, B, and C. In the mirror forms of my said Cases A, B, and C I secure coincidence by pivoting either one or both of the 25 mirrors. Thus by pivoting mirror, M , for instance, on pivot, 34, image, I' , can be made to move around to I'' , along an arc $I'I''$ whose center is at 34' where mirror N forms the image of pivot 34. As the full size image I' moves to I'' back of and into alignment with the object point I , the reduced image i' of I' , at the same time moves down and back of i . The connection between the 30 optical elements and the camera parts in Fig. 1 to produce the rotation is established through an arm 35 fixed to mirror M , a link 36, a lever 37 and a link 38 connected to that part 35 of the camera which holds the plate or film holder. The lever 37 is pivoted at 39 to an arm 40 mounted on the lens supporting part of the camera. Now suppose the link 38 to be removed so that the mirror M may be kept fixed in its parallel relation to mirror N . The full size image I' will then 45 be invariably fixed with relation to its object I , and image coincidence, for the eye at 75, can no longer be secured except by relative displacement of the reduced images i and i' , as by dividing lens, S , diametrically 50 on the vertical plane perpendicular to the mirrors and by making its thus disunited halves slide by each other. In this case the mirror N is preferably made totally reflecting or non-translucent, and one half of it is suppressed so that the remaining half N' , Fig. 2, with its corresponding-left half S' of the lens may serve exclusively for one-half of image, i' ; the other or right half S'' of the lens then serves alone and exclusively 55 for the complementary half of image, i .

An expensive but simple and easily understood form of this device is shown in perspective Fig. 3, where the fixed parallel mirrors, M^2 , N^2 , are the end faces of a glass prism, 10, and the divided lens is formed by 70 grinding a concave, half in the prism and half in an adjacent glass block, 11. Prism, 10, may be mounted as in Fig. 4 on the side of the lens carrier, and block, 11, which, as the camera depth is varied, must slide up 75 and down along prism, 10, to preserve the coincidence of the images of objects in focus, is to this end provided with suitable guideways 13 and receives its vertical motion from a cam 14 on the bed 72 of the camera through 80 a leg 15.

The plate or film holding part of the camera is designated by 71 and the observer's eye by 76.

In cheaper forms the object mirror is 85 made so as to project beyond the median plane as indicated for object mirror M' at 12 in Fig. 2, and the divided lens is made accurately enough by splitting a common minus lens and smoothing its split edges. 90

As Figs. 2 to 4 have become the most important figures of the present application, Case D, the complete theory involved is illustrated in the supplemental diagram Figs. 10 and 11. Fig. 10, with the two half 95 lenses S' , S'' held to act as a single lens, illustrates the optical principles involved when the mirrors M and N are parallel and the mirror M is pivoted at 34. The object point to be sighted on being at I , its image, 100 after reflection in mirror M and then in mirror N , is at I' , where the vector II' is perpendicular to the mirrors and equal to $2d$ or twice the distance d between their parallel reflecting planes and this, as shown in Fig. 105 13, of my said Case A, is true for all possible distances of the object point I .

As clearly seen in Fig. 11, the nearer and movable lens half S' of the divided lens has its principal foci at E' and G' and its almost coincident nodal points may be considered as merged in one point C' . Similarly, the farther and here stationary half lens S'' , Fig. 11, has its principal foci at E'' and G'' and its two nodal points roughly 110 merged in center C'' . In Fig. 10, where the distances $E'E''$, $C'C''$, and $G'G''$ are all three *nil*, the two half lenses act as a single lens to form an image i of I and an image i' of I' . By turning the mirror M clockwise 120 on its pivot 34 through an angle alpha (α), as indicated by arrow 17, the image I' is caused to turn counterclockwise along the arc $I'I''$, whose center is at 34' (which is the image of 34 in N), through an angle beta 125 prime (β'), which equals beta (β), or twice angle alpha (2α). This brings image I' down along arc $I'I''$ to I'' , where it appears alined with I so that its image i' must likewise have moved down to a position a trifle 130

back of i . This, in accordance with the principles of my said Case A, makes pivot 34 correspond to point A in the theoretical form, Fig. 23, of my said Case A. See also Fig. 10 of my said Case A, where O^2 corresponds to the present image I'' .

Fig. 11 illustrates the optical principles involved when image coincidence is secured, in the combination of Fig. 1, by leaving the mirrors parallel and lowering the nearer half lens S' as indicated in Fig. 2. The downward displacement of the half lens S' necessary to secure coincidence is indicated in Fig. 11 by $G'G''$, which is determined by producing the line $I'C''$ to G' , where it meets the vertical focal plane through G'' . The half lens S' having been lowered by this amount, as illustrated in Fig. 11, forms the image i' of I' in the axis $E''G''$ of the stationary half S'' directly behind i , which is left as an unblacked dot for clearness.

The pivot 34 of Fig. 10 having completely disappeared in Fig. 11, the ray inclinations in Fig. 11 are determined by angle gamma (γ), which is smaller than angle beta (β) in Fig. 10, as its apex is at c' , which is the second reflected image of center C'' , whose first reflected image is at c . This apex c' corresponds to pivot A in the theoretical form, Fig. 23, of my said Case A. One station point of the focuser is situated at C'' of the stationary half lens S'' ; and the other station point is situated at c' , which is the said second mirror image of station point C'' . Point C'' as a point of the stationary half lens S'' admits and transmits the direct ray $IC''G''$; and the same point C'' considered as a point of the lowered lens S' admits the inclined ray $I'C''$ and transmits it as $C''G''$ so that the lowered lens acts to refract the incident ray $I'C''$ at C'' through an angle $I'C'I$ or gamma prime (γ'), which is variable at will by varying the distance $C'C''$. When $C'C''$ is *nil* angle gamma prime (γ') is *nil*, which can only be true when vector II' is at infinity.

In forms in which coincidence is obtained by relative motion of the mirrors the lens may be dispensed with altogether which amounts to the same thing as employing a lens of infinite focus, that is, a piece of plain plate glass. Considered as a lens, such a plate forms the image of any object within and of the same size as the object itself, and hence the images, i and i' , of object, I , and of its image, I' , coincide with such object and image, that is, have the same size and position as their originals. In this case it is clearly seen that coincidence of the images can only be apparent, as there is no real coincidence of images except of the retinal images within the observer's eye. Thus in Fig. 1 turning mirror, M , clockwise causes image, I' , to move from I' to I'' and this in turn causes the retinal images to meet and co-

incide. My object is in all cases sufficiently and fully attained by nothing more than this coincidence within the observer's eye.

I shall describe forms in which no mirrors are used and one of these in which the coincidence of the images is not only mental and in the eye, but external as well. One of these forms without mirrors is shown diagrammatically in Figs. 5 and 5^a, the latter being a view in the direction of arrow 18, Fig. 5, with camera parts omitted for clearness. L, B and H represent the lens, bellows and plate holder of a camera, which is provided with means (not shown) for adjusting the depth or distance between L and H. On the lens holding frame are fixed two similar diminutive cameras or finders, F and V, each comprising a case, 3, lens, 4, and screen, 5. To facilitate the description, these finders are supposed to be one over the other in the same vertical plane. On the plate holding frame, H, is fixed a prism, P, which, as seen in Fig. 5^a, is set to apparently overlap one-half of the lower finder, V. For the observer, whose eye is at 7, the part of finder, V, which lies behind the prism is by refraction apparently dropped to V' and in its original place is seen the half, F', of the upper finder, F. If a horizontal bar be viewed in the finders 8, 9, the right half, 9, of which will be dropped by refraction to 9' and the same bar will form in the lower finder an image, 10, 11, part, 10, of which appears directly as 100 seen in Fig. 5^a and part, 11 (dotted), as dropped to 11'.

By varying the depth of the camera the half image, 9', can be moved up and down and be made to register with half image, 10, and form therewith a continuous image. On the other hand, if the original bar moves farther away from or closer to the camera, the half images, 10 and 9', will be either separated or approached because their originals, 10 and 9, on screens, 5, are separated when the object approaches, and vice versa. The continuity of the image, therefore, depends simultaneously upon the distance of the object and the depth of the camera; and I have discovered that in this case, as in the preceding, the parts can always be proportioned and adjusted, by calculation or by direct observation, to secure exact correspondence between the camera and the focuser for two different distances of the object point. The great advantage of this form is that in it the mechanical connections with the camera are as simple as they can well be. If the lenses, 4, are large in diameter as compared with their focal length, the screens, 5, may be omitted. No screens can be used with minus lenses, but in this case the motions are reversed. I have secured this reversal by simply cross connecting the parts 120 125 130

as shown in Fig. 6 so the prism shall move with the camera lens and the finder lenses with the camera plate holder. When lenses without screens are used it is better to add 5 prisms, p , q , Figs. 7 and 8 which permit of securing a better field.

In Fig. 8 by the use of reversed prisms, 27, 28, the arrangement is made symmetrical and optically better, because in it the refractions are less than in the preceding forms, and colorations are avoided by the reversal 13 of prisms. In all the prism forms so far described the indications depend solely on the depth of the camera and are not appreciably 15 affected by lateral displacements or vibrations. This is a great advantage.

In Fig. 9 I show a form in which the coincidence of the images is real, as well as apparent. The camera shown dotted carries 20 externally on its plate holder a screen, 29, and on its lens holder a pair of prisms having one face spherical. These prisms act like small eccentric lens elements, that is, like lenses of considerable depth of focus so 25 that each produces on the screen an image which remains clear through considerable movements of the screen. Thus by moving the screen, 29, from 37 to 39 the image formed by the upper lenticular prism may 30 be considered as moving with the screen, but along line 47, that is, to have an up and down motion on the screen. Similarly, the image formed by the lower lenticular prism 35 also moves down and up as the screen is reciprocated between 37 and 39. When both images are observed together and screen, 29, is moved from 37 to 39 the two images shown as round dots are seen to first approach until they meet at 43 and then separate. By 40 giving the prisms an angle and a separation that will make their refracted rays cross like those of the camera lens and by giving them about the same curvature as the lens, the prismatic arrangement will by coincidence 45 or separation of images indicate whether the camera is or is not in focus on a given object. One disadvantage of this form as compared with the others is that it does not indicate directly in which direction 50 the camera may be out of focus, unless the images are identified by momentarily covering one of the two prismatic lenses.

All the devices described are combined to produce eventually two retinal images which 55 may be relatively moved within the observer's eye and there brought into actual coincidence; whether the outside images do or do not actually coincide is immaterial.

NOTE 1.—The correspondence that must 60 exist between focusing displacements of the camera parts or image distances on the one hand, and the relative inclinations of the two sighting directions on the other hand, are subject to the principles set forth in 65 Figs. 23 and 24 of my said Case A, and

with the aid of such disclosures in my said Case A the cam in present Fig. 4 can always be plotted and constructed to yield an all-point correspondence, but it is more simply made, as in my said Case C, to secure 70 only 2-point correspondence.

NOTE 2.—Where the lens is to serve as a true finder lens the lower mirror M^2 , Fig. 3, should be made much larger than shown, as will be quite evident in view of the disclosure 75 made in lines 58 to 78, page 16, and Fig. 37 of my said Case A.

NOTE 3.—Wherever I speak of an image as being "formed" I use this term as it is always used, in the science of optics, without reference as to how much or how little of the "formed image" is visible, for this varies with the position of the observer's eye and with details of construction that have no effect on locating the image. Thus 85 in Fig. 7 of my said Case A, where O^2 represents an image "formed" by the plane mirror N , the observer can see more and even all of this image O^2 by simply shifting his eye to the left. This is in accordance 90 with the oldest terminology of the science as proved by "An Elementary Treatise on Optics" designed for the use of the cadets of the United States Military Academy by Wm. H. C. Bartlett, A. M., professor of experimental philosophy in the Academy, N. Y., 1839, article 57, pp. 66 and 67.

NOTE 4.—Every mirror, lens, half lens, or prism, shown in my Figs. 1 to 11 and considered *per se*, is an "image forming device." 100

NOTE 5.—The fact that a half lens forms as complete an image as a full lens was laid down as an optical principle, in 1754, by John Dollond, who substituted two half lenses for the two full lenses originally used 105 in the Bouguer heliometer. See the *Philosophical Transactions*, vol. 48, part 2, for the year 1754, London, 1755, page 552, Observation 4.

NOTE 6.—Lalande in his *Astronomie*, 110 Paris, 1771, vol. 2, plate 26 (copy at the Library of Congress) shows in Fig. 186 the two lens heliometer of Bouguer and in Fig. 187 the now well known divided lens equivalent of Dollond; but all these lenses are convex and I believe that I am the first to make or use a divided lens that is divergent instead of convergent.

NOTE 7.—I am aware: first, that each of the optical focusers shown in my Figs. 1 to 120 9, is virtually a short base range-finder of the type having its relatively short base line in the instrument with means for forming two simultaneously visible and relatively movable object-point images of the one object point to be focused on; I am aware secondly, that two image range finders, considered *per se*, are old and well known and have been fully described for instance, by Barr and Stroud in *Institution of Mechanic 130*

cal Engineers, Proceedings, London, January 1896, pages 33 to 78, plates 1 to 12; I am aware, thirdly, that the said Barr and Stroud article under the head "Methods of producing alignment" pages 39 and 40, Figs. 17 to 20, shows and discusses various methods of producing the said two relatively movable images, as by a pivoted mirror in Fig. 17, or a sliding lens in Fig. 18, or a sliding prism in Figs. 19 and 20; and therefore I do not claim any matter so shown or previously disclosed by others.

What I claim as my invention and desire to secure by Letters Patent is:—

- 15 1. The combination with a focusing camera, of two fixed mirrors, and a divided lens, one-half of which is adapted to view the object directly and the other half adapted to view it by reflection in the mirrors, and connections between the camera and the lens elements to cause the latter to relatively slide so any object whose direct and reflected images apparently register shall be in focus in the camera.
- 20 2. The combination with a focusing camera, of two fixed parallel mirrors, and a divided lens, one-half of which is adapted to view one part of the object directly and the other half adapted to view the complementary part of the object by reflection in the mirrors, and connections between the camera and the lens elements to cause the latter to relatively slide so any object whose direct and reflected images apparently register shall be in focus in the camera.
- 25 3. The combination with a photographic camera comprising relatively movable parts adapted to be relatively moved to set the camera in focus on an object point of the camera field; of an optical focuser, for said camera, comprising image forming elements adapted to receive, and then collect for final transmission, two distinct and differently directed groups of rays which are really emitted from the said object point toward two separated stations of the said focuser and which are collected for final transmission to the eye as being virtually emitted from two different but simultaneously visible object point images which have a relative position that varies with variations produced in the initial ray inclinations by changing the distance of the said object point; said focuser comprising, moreover, relatively translatable focuser elements whose translatory or rectilinear displacement is adapted to produce changes in the relative position of the said two object point images, to permit of bringing said two object point images, at will, into a characteristic relative position that has been selected as the focusing-indicating position for the camera; structural connections between the said relatively translatable focuser elements on the one hand, and the said relatively movable camera parts on the other hand to insure that to each relative position of the camera parts shall correspond only one angular value of ray inclinations at their origin in the said object point when the said two relatively movable object point images of such object point have been brought into the said characteristic focus-indicating relative position; said relatively translatable focuser elements consisting in the relatively movable parts of a divided lens.
- 30 4. The combination with a photographic camera comprising relatively movable parts adapted to be relatively moved to set the camera in focus on an object point of the camera field; of an optical focuser, for said camera, consisting in a range finder of the type having its base line on the camera; separated and relatively fixed mirrors for determining the two end stations of said base line; means coöperating with the said fixed mirrors for forming two proximate and simultaneously visible images of the said object point showing it as viewed virtually from the said two end stations; such image forming means comprising relatively movable optical elements whose relative mo-

era parts on the other hand to insure that to each relative position of the camera parts shall correspond only one angular value of ray inclinations at their origin in the said object when the said two relatively movable object point images of such object point have been brought into the said characteristic focus-indicating relative position.

- 45 5. The combination with a photographic camera comprising relatively movable parts adapted to be relatively moved to set the camera in focus on an object point of the camera field; of an optical focuser, for said camera, comprising image forming elements adapted to receive, and then collect for final transmission, two distinct and differently directed groups of rays which are really emitted from the said object point toward two separated stations of the said focuser and which are collected for final transmission to the eye as being virtually emitted from two different but simultaneously visible object point images which have a relative position that varies with variations produced in the initial ray inclinations by changing the distance of the said object point; said focuser comprising, moreover, relatively translatable focuser elements whose translatory or rectilinear displacement is adapted to produce changes in the relative position of the said two object point images, to permit of bringing said two object point images, at will, into a characteristic relative position that has been selected as the focusing-indicating position for the camera; structural connections between the said relatively translatable focuser elements on the one hand, and the said relatively movable camera parts on the other hand to insure that to each relative position of the camera parts shall correspond only one angular value of ray inclinations at their origin in the said object point when the said two relatively movable object point images of such object point have been brought into the said characteristic focus-indicating relative position; said relatively translatable focuser elements consisting in the relatively movable parts of a divided lens.
- 50 6. The combination with a photographic camera comprising relatively movable parts adapted to be relatively moved to set the camera in focus on an object point of the camera field; of an optical focuser, for said camera, consisting in a range finder of the type having its base line on the camera; separated and relatively fixed mirrors for determining the two end stations of said base line; means coöperating with the said fixed mirrors for forming two proximate and simultaneously visible images of the said object point showing it as viewed virtually from the said two end stations; such image forming means comprising relatively movable optical elements whose relative mo-

tions are adapted to cause a relative motion of the said two object point images; and structural connections established between the said relatively movable camera parts on the one hand and the said relatively movable focuser parts on the other hand to insure that to each relative position of the said

camera parts shall correspond only one relative position of the said relatively movable focuser parts.
